UNITED STATES PATENT OFFICE

2,411,243

BOBBIN-IDENTIFYING DEVICE FOR
WINDING MACHINES

Gustaf S. Beckman, Cranston, R. I., assignor to
Universal Winding Company, Boston, Mass., a
corporation of Massachusetts

Original application April 10, 1944, Serial No.
530,407. Divided and this application June 21,
1945, Serial No. 600,744. In Great Britain July
2, 1941

7 Claims. (Cl. 242—1)

1
This application is a division of application, Serial No. 530,407, filed April 10, 1944.

The present invention relates to winding machines for winding yarn, thread and similar textile materials into packages such as cops, bobbins, pirns and the like. More specifically, the invention consists in means for automatically applying identification marks to the wound bobbins in the machine before they are doffed therefrom.

In the present specification and claims the term "yarn" is employed to indicate all kinds of attenuated material and the term "bobbin" is used to designate the wound package whatever its form or character.

It is a common practice in textile mills to identify filling yarn by marking the bobbins with crayon or chalk to indicate different types and counts of the yarn and also to identify the machine or department in which the yarn is processed or handled. Usually, the operator of the machine marks the yarn on the bobbin by drawing a piece of chalk or crayon over the surface of the bobbin, but this operation has certain disadvantages as it is liable to cause the chalk dust to infiltrate into the mechanism of the machine to interfere with its proper functioning.

The practice of marking the bobbins as now generally used is for the purpose of preventing mixed counts of filling yarn going to the same loom and becoming incorporated in the fabric. In such case the difference in the size or count of the filling does not become evident until the cloth is woven and therefore it results in spolage or seconds in the product of the mill. When the bobbins are properly marked the weaver can discover if mixed yarn is furnished to the weave room and place the responsibility in the winding room or other department of the mill where the yarn was processed or handled. In other instances, by applying several distinguishing marks to the yarn on the bobbin its progress from the source can be followed and when poor or imperfect bobbins reach the weave room they can be traced to the machine in which they were wound or to the department in which the yarn was processed. In some cases different types or counts of yarn are wound on different spindles of the same machine and the bobbins may become mixed through carelessness of the operator, as by the dropping of bobbins on the floor or by incomplete emptying of the collecting boxes for one type of yarn before bobbins of another type are placed therein.

Most mills handle more than one count of yarn at the same time and as the counts must be kept separate it is an object of the present invention

2
to provide automatically-operated means for marking the bobbins in the winding machine with one or more distinguishing colors to prevent mixed counts from being woven in the loom; and further; to trace the steps in the processing of the yarn in different departments of the mill to correct defects or deficiencies in its manufacture.

Another object of the invention is to provide bobbin-identifying means which may be employed as an attachment on winding machines in which the bobbins are doffed either manually or automatically upon completion of the winding.

Another object of the invention is to provide means incorporated in an automatic winding machine for marking the bobbins with identifying indicia at the completion of the winding before they are doffed from the machine.

Another object of the invention is to provide a device which may be applied to winding machines to mark the bobbins produced therein with different colors applied by means fed from reservoirs containing fugitive ink or dye liquid.

Further objects of the invention are set forth in the following specification which describes one form of construction of automatic bobbin-identifying means as illustrated by the accompanying drawing.

In the drawing:

30
Fig. 1 is a side elevation of the essential mechanism of a bobbin-winder showing means for marking the yarn on the bobbin by traversing stylographic marking devices along its side with electrically-controlled means for operating the same;

Fig. 2 is an enlarged end view of the bobbin showing the series of styli or feeding means for the dye liquid; and

40
Fig. 3 is an enlarged plan view of a portion of the device showing the movable slide or element which traverses the marking device along the side of the bobbin as it is held in connection with the winding spindle.

While the present invention may be applied to use with either manually-operated or automatic winding machines, it is herein described and illustrated in connection with a machine of the type disclosed in United States Letters Patent No. 2,257,651, dated September 30, 1941, and No. 2,302,715, dated November 24, 1942. The machines illustrated in these prior patents are completely automatic for donning empty cores or yarn-carriers, winding the yarn thereon, and doffing the bobbins as they are completed. It is therefore desirable that machines of this type

shall be further adapted for marking the bobbins automatically to identify them after they have been delivered therefrom. On the other hand, it is to be understood that the present invention is not limited to use with automatic winding machines, but may be applied to other types of winders for marking the bobbins before they are doffed.

Referring to the drawing, in Fig. 1 the frame or casing of the winding machine is indicated at 2 and projecting from bearings therein is a rotary winding spindle 3 at the end of which is a cup-shaped member 4 for receiving the head *h* of a wooden core or bobbin *b* such as used in automatic filling-changing looms. The opposite or tip end of the bobbin *b* is held in a similar recessed member 5 on a spindle 6 mounted free to rotate in a bearing sleeve 7 supported by a suitable bracket, not herein shown, attached to the side of the machine frame 2. In the type of machine herein illustrated the yarn *y* is wound on the core or wooden bobbin *b* by means of a thread-guide 10 which has a relative traversing motion axially of the bobbin and is progressively advanced longitudinally thereof to deposit the yarn in courses of cross-wound coils which overlap at their forward ends. In this way the bobbin grows by longitudinal extension, being formed with a conical base, a cylindrical body portion and a tapered or conical tip end.

The thread-guide 10 is carried on a reciprocable traverse-rod 15 mounted to slide longitudinally in a bearing in the frame or casing 2. The traverse-rod 15 is reciprocated longitudinally in its bearing by a suitable cam or similar means enclosed within the frame or casing 2 of the machine, but not herein illustrated as such traversing mechanism is well known to those versed in the art. The yarn *y* delivers from its source of supply, supported above the machine but not herein shown, and feeds to the bobbin through an eyelet 17 in the thread-guide 10. Connected to the thread-guide 10 is a rotatable contact-disk or traverse-wheel 20 mounted on a sleeve-like nut 21 which is interiorly threaded to engage the screw-threads 22 on the traverse-rod 15. It will be understood that the thread-guide 10 is positioned adjacent the rearward or butt end of the yarn-carrier or wooden bobbin *b* at the start of the winding and the traverse-wheel 20 is so related thereto that each time the guide makes a return stroke to the left, as viewed in Fig. 1, the periphery of the wheel will contact the yarn wound on the bobbin to turn the nut 21 through a part of a rotation to feed the guide forward to a slight extent along the traverse-rod 15. This method of advancing the layers of winding along the bobbin by the intermittent feed of the thread-guide is illustrated and described in the prior patents referred to above and is well known to those versed in the art.

At the completion of the bobbin the thread-guide 10 will be positioned at the forward or tip end of the bobbin when at the furthermost limit of its forward stroke and at this point the guide, or a part connected therewith, engages a stop or abutment to move the latter to cause actuation of the stopping mechanism of the machine; this mechanism being employed generally in machines which require manual doffing and donning. In automatic machines such as described in the patents referred to above, the completion of the bobbin effects initiation of the operation of means for doffing the wound bobbin, donning an empty core or yarn-carrier, severing the yarn from the

5 doffed bobbin, attaching the end of the yarn to the empty carrier, returning the thread-guide to initial winding position, and again starting the winding operation. The automatically-operated mechanism for performing these functions is described in the prior patents before mentioned and is not referred to specifically herein as it forms no part of the present invention.

10 The wound bobbins may be marked with several different colors, for example red, yellow and green, to indicate the size or count of the yarn and other particulars such as the department in which the yarn was spun or processed, or in other cases the particular machine in which the bobbins were wound. The colored markings remain on the yarn when it is woven into the cloth, but when the fabric is later processed or finished, the dye, being fugitive, will disappear on treatment with water or other liquids.

15 Figs. 1 to 3, inclusive, illustrate automatically-operated mechanism for applying identification indicia to the bobbins before they are doffed or removed from the winding spindles, this mechanism comprising a sliding or traveling element for carrying the marking device and means for traversing it longitudinally of the bobbin to apply the indicia thereto. Referring to U. S. Patent No. 2,302,715, mentioned above, the movable yarn-retriever described and illustrated therein 20 provides a convenient means for moving the marking device along the length of the bobbin. In the machine of this patent the yarn-retriever 35, shown in the present drawings, is slidable along a rod 36 and provided with a double-pronged hook 37 which passes in under the thread-guide 10 when the latter is at the tip end of the bobbin to take a loop of the yarn *y* therefrom and carry it back toward the spindle-cup 4 to place it thereacross for attachment to an empty bobbin when the latter is donned.

25 The yarn-retriever 35 is actuated at the completion of winding a bobbin *B* to cause it to be slid along the rod 36 from the position shown by full lines to that indicated by dash lines in Fig. 1. The means for actuating the yarn-retriever may comprise a series of levers operated by an electromagnet 38. Pivoted at 39 to a bracket 40 supported from the machine frame 2 is a lever 41 having its lower end connected to the yarn-retriever or slide 35 by means of a slot 42 engaged by a pin or stud 43 fastened to the slide. A link 45 pivotally connected to the lever 41 at one end is similarly joined at its opposite end to a bell-crank lever 46 pivoted at 47 on the bracket 40. The lower arm 48 of the bell-crank 46 is connected by a link 49 to a second bell-crank 50 therebelow pivoted at 51 on a fixed support represented at 8 in Fig. 1 of the drawing. The upper arm of the bell-crank 50 is pivotally connected to a link 52 which is similarly joined to the end of a plunger-armature 55 which is slidable by energization of the electromagnet 38. A helical spring 56 fastened to the upper arm of the bell-crank 50 at one end and anchored at 51 to the machine frame 2 normally tends to maintain the bell-crank 50 in the position illustrated in Fig. 1 with the bell-crank 46 rocked to hold the yarn-retriever or slide 35 outwardly beyond the end of the winding bobbin *B*. In the machine of the prior Patent No. 2,302,715 the electromagnet or solenoid 38 is energized by the closing of a switch which is operated automatically upon completion of the winding of the bobbin; suitable means for this purpose being illustrated and described in said

patent. Upon energization of the solenoid 38, its armature 55 is attracted to draw it to the right, as viewed in Fig. 1, thereby causing the bell-crank 50 to be operated to slide the link 49 upwardly and rock the bell-crank 46 in counterclockwise direction. The lever 46 is thus caused to move the link 45 to rock the lever 41 and slide the yarn-retriever 35 from the position illustrated in full lines to that indicated by dash lines in Fig. 1.

The yarn-retriever or movable element 35 is employed as a means for marking the bobbin by forming it with or attaching a part thereto constructed as a support for a plurality of styli or similar devices for applying colored indicia to the yarn on the bobbin B. As shown in Figs. 1, 2 and 3, an angular bracket or support 60 is attached to the rearward side of the hook 37 carried by the retriever or slide 35 by means of screws 62 to serve as a support for a plurality of vials 63 adapted to contain the fugitive ink or dye liquid *f*. The vials 63 are clamped to the bracket 60 by means of a fluted strap 64 fastened thereto by screws 65, as shown most clearly in Fig. 1, in position one above another with their mouths or openings upright, see Fig. 2. Each stylus has a small tubular nozzle 66 projecting forwardly therefrom with one end dipping into the liquid *f* and its opposite end arranged in position to contact the side of the bobbin B, whereby capillary attraction will cause the ink or liquid dye to feed through the nozzle and be applied to the yarn on the bobbin as the yarn-retriever or slide 35 is moved longitudinally of the bobbin to the position indicated by dash lines in Fig. 1.

The method of operation of the present embodiment of the invention is explained as follows: At the completion of winding the bobbin B the solenoid 38 is energized through the means of an automatically-operated switch in the electrical circuit to cause its armature 55 to operate through the link 52, bell-crank 50, link 49, bell-crank 46 and link 45 to rock the lever 41 and slide the yarn-retriever 35 toward the left. At this juncture the thread-guide 10 is at the outer or finishing end of the bobbin B, as shown in Fig. 1, and the hook 37 on the yarn-retriever will be slid under the guide to cause it to engage the yarn *y* and extend a loop toward the left. As the yarn-retriever 35 slides along the side of the bobbin B the nozzles 66 make contact with the yarn thereon to apply a series of colored lines or markings thereto. After this operation has been completed the spindle-cup 4 is withdrawn to release the bobbin to doff it from the machine.

While this automatically-operated means for marking the yarn on the bobbin before it is removed from the machine is shown in connection with the electrically-actuated yarn-retriever disclosed in the patent last referred to, it is to be understood that the invention is not limited to this form of construction of the device as the marking device might be embodied in any movable part of the winding machine and actuated either manually or automatically before the bobbin is doffed, either manually or automatically, the only requirement being to provide relative movement between the bobbin and the

marking means. Likewise, the vials containing the marking liquid might be dispensed with and chalk or crayons employed in their place.

It will be observed from the foregoing specification that the present invention provides means for applying identifying indicia to the yarn on filling bobbins or other forms of packages whereby to indicate the character of the yarn and its source of manufacture. While the device is herein shown as embodied in a preferred form of construction, it is to be understood that various modifications may be made in the structure and arrangement of the parts of the device and the manner of applying it to use without departing from the spirit or scope of the invention. Therefore, without limiting myself in this respect, I claim:

1. In a winding or like machine, means for packaging yarn on the machine, an element movable longitudinally of the package, and means carried by said element and adapted to contact the yarn on the package to apply identifying indicia thereto.

2. In a winding machine, the combination of means for winding a bobbin, a marking device, and means for effecting relative movement between the marking device and bobbin longitudinally of the latter to cause the marking device to contact the yarn on the bobbin to apply identifying indicia thereto.

3. In a winding machine, the combination of means for winding yarn on a bobbin, a member slidable longitudinally of the bobbin, means operated automatically upon completion of the bobbin to slide said member, and means carried by said member for contacting the yarn on the bobbin to apply identifying indicia thereto.

4. In a winding machine, the combination of means for winding a bobbin, a member slidable longitudinally of the bobbin, means for sliding said member upon completion of the bobbin, and a vial carried by said member and adapted to contain marking liquid, said vial having means communicating with the fluid therein and adapted to contact the yarn on the bobbin to mark the latter with identifying indicia.

5. In a winding machine, the combination of means for winding a bobbin, a member movable relatively of the bobbin, means carried by said member for contacting the yarn on the bobbin to mark the same with identifying indicia, and electrically-operated means for moving said member.

6. In a winding machine, the combination of means for winding a bobbin, a member movable relatively of the wound bobbin, means carried by said member for marking indicia on the yarn on the bobbin, an electro-magnet, and means connecting said electromagnet to move said member to cause the marking means to contact the yarn on the bobbin.

7. In a winding machine, the combination of means for winding a package of yarn, a member movable relatively of the package, a plurality of vials containing marking liquid, means for mounting said vials on the movable member, and means communicating with the liquid in the vials and adapted to contact the side of the package to apply identifying indicia thereto as the member moves longitudinally of the package.

GUSTAF S. BECKMAN.
